WILLIAM SCHWARZE, OF PHILADELPHIA, PENNSYLVANIA, ASSIGNOR TO RUDOLPH H. WYNER, OF BOSTON, MASSACHUSETTS.

SPRING-NEEDLE KNITTING-MACHINE.

1,386,431.

Specification of Letters Patent.

Patented Aug. 2, 1921.

Application filed May 15, 1920. Serial No. 381,788.

To all whom it may concern:

Be it known that I, WILLIAM SCHWARZE, a citizen of the United States of America, and resident of Philadelphia, in the county 5 of Philadelphia and State of Pennsylvania, have invented new and useful Improvements in Spring-Needle Knitting-Machines, of which the following is a specification.

This invention relates to knitting 10 machines, and more particularly to that class of machines which employ independently actuated needles of the spring beard type.

In machines employing spring beard needles it is necessary to provide some means 15 for closing the needle beard during the shedding of the old loop. Various devices have previously been employed for this purpose, and in some cases have taken the form of independent, cam actuated beard closers 20 associated with the several needles and which are projected into engagement with the needle beards for closing the latter at the proper time in the knitting operation. In the practical employment of such devices 25 commonly found in the art, it has been found that the effect on the needle beard is so harsh that the latter is bent or broken very quickly, adding greatly to the expense of upkeep and frequently seriously damage- 30 ing the product of the machine, while many of such arrangements are impractical for use with fine gage knitting machines.

The present invention seeks to avoid so far as possible, such undesirable features of 35 previous beard presser means, and has for its object the provision of means for closing the beards in an improved manner and as one mode of accomplishing this result may provide for flexing the needles outwardly as 40 they pass the knitting point, whereby to bring their beards into closing contact with a relatively fixed beard presser. In order to secure the most beneficial results from such an operation it is found desirable to so ar- 45 range the flexing means that the needle shall be flexed about a point as remote as practicable from the beard. The needle shank being somewhat resilient, and substantially unsupported throughout a large portion of 50 its length, this arrangement makes it possible for the hook end of the needle to adjust itself to a certain extent during the pressing operation, whereby the closing action is ex- tended over a greater period of time than

usual, all harshness of action is avoided, and 55 only the necessary closing pressure between the presser and beard is secured.

For the purpose of flexing the needles outwardly for pressing the beards, the needles may be arranged to have a secondary move- 60 ment imparted to them during their retraction, and an object of the present invention is to provide effective means for producing such movement. Such means may for example comprise the employment of needles 65 having surfaces inclined relatively to their axes, such surfaces preferably being formed upon rearwardly projecting humps on the needle shanks and adapted to coöperate with other parts in securing the desired move- 70 ment. Such other parts may take the form of elements arranged to lie in the path of said surfaces as the latter are retracted, the relative inclination of such surfaces and ele- 75 ment being such as to force the needles outwardly during their descent.

As it is desirable for a purpose herein- 80 after referred to, to vary, at times, the oper- erative relations of said surfaces and ele- ments, one of the objects of the present in- 85 vention is to provide suitable arrangements of parts to permit such operation and a pre- ferred mechanism for carrying into effect such arrangements in accordance with the present invention may desirably consist in 85 the provision of cam operated jacks mount- ed to move relatively to the needles and hav- 90 ing inclined ends constituting the elements above referred to. Such jacks may if de- sired be mounted to slide in the needle 90 grooves behind the needles although such an arrangement is in no sense essential to the carrying out of this part of the invention as it is contemplated that other arrangements 95 of jacks and engaging needle shank surfaces may be successfully employed for such pur- 95 poses.

To further lessen the strain on the beard during the knitting operation, the knitting 100 cams and the cams for actuating the needle flexing means, which as herein illustrated take the form of independent jacks located behind the needles, are so relatively ar- ranged that the closing of the needle beard takes place at an intermediate portion of the 105 needle retraction, the beard remaining closed until the cast-off point is reached, at which time the needle is permitted to spring back

quickly to normal position. In this manner the beard is subjected to but a single pressing action as by reason of the rapid and early straightening of the needle, the needle beard fails to come into pressing contact with the presser during the up-stroke of the needle.

One specific mode of accomplishing the objects of the invention as above pointed out 10 has been herein described and illustrated as an instance only of the forms in which it may be realized.

In the annexed drawings—

Figure 1 is a partial vertical section 15 through the cylinder of a knitting machine adapted for the employment of the present invention, showing the needle in its most elevated position;

Fig. 2 is a front elevation on smaller scale, 20 of the interior of that portion of the cam cylinder which contains the knitting cams;

Fig. 3 is a diagrammatic elevational view 25 showing the successive positions of successive needles in taking the yarn and forming the stitch, and showing the relative positions of the needles and jacks during this operation;

Fig. 4 is a top plan view of that portion 30 of the cam cylinder shown in Fig. 2;

Figs. 5, 6 and 7 are diagrammatic views 35 illustrating successive stages of the beard pressing operation. 1 indicates the needle cylinder provided on its outside surface with slots 2 for the reception of the needles; 3 is the cam cylinder upon the interior surface of which are mounted the cams for actuating the needles; 4 is a web-holder bracket secured in usual manner to the cylinder, and provided at 5 with a dial in which 40 are mounted web-holders 6. These web-holders are provided with butts 7 which may be operated by cams contained in a cam ring 8 mounted upon the dial in usual manner; 9 is a needle movable in the slot 2, said 45 needle being provided with a spring beard 10 and having at its lower end a butt 11 arranged for actuation by the needle cams.

As herein shown the needle grooves are 50 cut deeper than is the usual practice, and in the bottoms of said grooves and behind the needle shanks are provided slidably jacks 12, said jacks being provided with butts 13 for actuation by cams to be hereinafter described. At a point intermediate the length 55 of the needle shank and preferably at some distance below the web-holders, each needle is provided with a rearwardly extending hump 14, said hump providing an upwardly and rearwardly inclined cam face 15. While 60 as herein shown, the hump is formed by bending the needle shank, it is clear that other arrangements for providing a suitable actuating cam surface for the needle may be employed in securing the desired result.

65 The upper end of each jack, as shown at

16, is provided with a downwardly and forwardly inclined cam face, the inclination of which is complementary to that of the cam hump of the needle, and which serves to cooperate therewith in a manner hereinafter 70 fully described.

The usual retainer springs 17 are provided for holding the needles in place within the slots of the needle cylinder. Resting upon the upper surface of the web-holder cam 75 ring 8 is a beard presser ring 18, said ring being held in position by means of a bracket 19 or any other suitable and desired manner.

The needle cam cylinder has secured to its inner surface needle lifting cams 20 and 80 21, and a needle depressing or stitch forming cam 22, said cams forming a cam path for engagement by the butts 11 of the needles, whereby the needles are given their stitch forming movement. Below the cams 85 20 and 21 is a second pair of cams 23, 24 respectively, which serve to raise the jacks 12, and for depressing the jacks a cam 25 is provided below the stitch forming cam 22. Above the uppermost point of the cam 90 21 a guard cam 26 is provided to prevent overthrow of the needles in their upward movement. 27 indicates a yarn guide of any usual and desirable form.

Referring now to Fig. 2, it will be noticed 95 that the upper portion of cam 23 is formed with a flat or inactive surface, constituting a dwell portion while the lower end of the jack depressing cam 25 is formed with a similar surface. It will also be seen that the 100 needle depressing cam is provided with an acute lower extremity, and furthermore that that portion of the cam 22 which acts to depress the needles is formed with a gradual downward curvature, while that portion of 105 cam 21 which serves to raise the needles is provided with a straight incline, such incline being substantially parallel to the incline of cam 24.

In the operation of the above mechanism, 110 the needles approach the knitting cams while in their upper position, as shown in Fig. 1, and as is indicated at the right hand portion of Fig. 3. In this position, as will be noticed by inspection of Fig. 1, the hump 115 14 of the needle is at a substantial distance above the upper end of the corresponding jack. As the needle butt comes into contact with the advancing portion of cam 22, it is caused to retract with accelerated velocity 120 due to the shape of cam 22 until it reaches the point indicated by the letter *a* in Fig. 2. This also corresponds with the position 125 of the needle as shown in Fig. 5. From this point to the point *b* (Fig. 2) and which corresponds with the position of the needles shown in Fig. 7, the needle continues to move downwardly while in contact with a relatively stationary jack, the butt of which 130 is at this time traveling along the level upper

surface of cam 23. During such relative travel of the needle and jack, the needle shank is wedged outwardly so that its beard is caused to intersect the vertical plane of 5 the inner edge of the presser ring. As shown in the successive Figs. 5 to 7, the needle after reaching this position is continued in its downward movement whereby the beard is pressed and is caused to pass 10 through the old loop carried upon the needle shank. As the point of operative contact of the cam portion 16 of the jack with the cam face 15 of the needle is at a very substantial distance from the hook end of the needle, 15 and as the needle shank is somewhat resilient, the closing of the beard is extended over an unusually long period of time and is cushioned to such an extent as to avoid any harshness in operation. 20 From the point *b*, Fig. 2, the needle butt continues to descend until it reaches the lower extremity of cam 2, and during this last portion of the needle movement, the jack butt travels down the advancing surface 25 of cam 25 in a path substantially parallel to the needle butt. By this means the flexure of the needle outwardly from the cam cylinder is maintained throughout the last part of the loop-drawing action, and although the needle is released from engagement with the presser member before its lowest point is attained it is maintained in its outwardly flexed position relatively to the web holders until after it begins to rise 30 up the slope of cam 21.

Immediately upon passing the lower extremity of the stitch cam 22, the needle butt is caused to rise along the advancing surface of cam 21, but during the first portion of 40 this movement the jack butt moves along the level lower surface of cam 25. The hump 14 thus rapidly leaves the surface 16 of the jack, whereupon the needle is free to spring backwardly in its slot and assume its normal vertical position, the web holders 6 advancing in time with the upward movement of the needles. The above action takes place at a point so early in the raising of the needle that the beard is removed from the vertical 45 plane of the edge of the presser ring before coming in contact with the latter, which thus avoids any second pressing of the beard on the up-stroke of the needle. The needle and jack now continue to move upwardly in 50 unison along the parallel cam surfaces of cams 21 and 24 until they reach their respective normal levels again, in which position they are ready for the next successive operation. 55

60 It will be noticed, by reference to Fig. 2, that by reason of the curved form of the retracting surface of cam 22, the downward movement of the needles is an accelerated one, and as during this movement of the 65 needle the latter is brought into contact with

the jack, the outward flexing of the needle and the pressure upon the beard is less pronounced at the beginning than at the completion of the operation. This results in a smoother and easier action which tends to 70 increase the life of the needles. The beard-pressing devices thus provided lie wholly external to the cylindrical surface defined by the bottoms of the slots in the needle cylinder, and it is, therefore, unnecessary to provide openings through the cylinder wall for the passage or reception of any of such devices. 75

While the above invention has been shown and described as particularly adapted to use 80 in circular knitting machines of the spring beard independent needle type, it is to be understood that the invention is not limited to such machines but that the claimed devices are applicable without change to machines of other types. 85

I claim:

1. A knitting machine of that type employing spring beard needles, comprising in combination, a needle bed having needle 90 guiding grooves therein, a needle beard presser member, means for producing relative movement between said presser and a needle mounted in one of said grooves in a direction longitudinally of the needle, and 95 means wholly external to a surface defining the bottoms of the several needle grooves, such means acting upon the needle at a point relatively distant from its beard and being operative to flex the needle transversely of 100 its length, whereby to bring its beard into contact with said presser.

2. In combination, in a knitting machine, a needle support, a spring beard needle thereon, a beard presser member, means for relatively moving said presser member and needle in a direction longitudinally of the latter, a device having an element movable into and out of operative engagement with the needle shank at a point relatively remote from the needle beard, and positive means for so moving said element, said device acting to flex the needle shank transversely about a point remote from the beard to bring the latter into contact with the 110 presser member. 115

3. In a knitting machine in combination, a spring beard needle, a beard presser member, means for imparting movement to said needle for drawing a stitch, and a needle 120 flexing device movable in a path substantially parallel to that of the needle in its stitch drawing movement and operative to flex the needle transversely to bring its beard into contact with said beard presser. 125

4. In combination in a knitting machine, a support having a needle slot therein, a needle movable in said slot, a jack also movable in said slot, means for moving said jack relatively to the needle and complementary 130

- cam elements carried by the needle shank and jack and tending when brought into contact to move the hook end of needle outwardly of its slot.
5. A knitting machine having in combination knitting instrumentalities including spring beard needles, a common beard presser for the needles, a device movable relatively to a needle whereby to cause the 10 closing of the needle beard by said beard presser, cam means for actuating said needle to form a stitch, and cam means for actuating said device, said respective cam means providing cam portions having parallel and 15 non-parallel portions.
6. In a knitting machine in combination a spring beard needle, a presser therefor, and a cam element operative by direct contact with the needle shank at a point below the 20 hook thereof, whereby to flex the shank to cause engagement of the needle beard with the presser.
7. In a knitting machine in combination, a spring beard needle, beard pressing means 25 therefor, a cam element arranged for direct contact with a portion of the needle shank at a substantial distance below the point of the needle beard, and means for moving the needle relatively to said cam element where- 30 by the latter is rendered operative to flex the needle to bring the beard into contact with the pressing means.
8. In a machine of the class described, in combination a spring beard needle, a presser 35 therefor, and a cam element movable relatively to the needle in a direction substantially parallel to the longitudinal axis of the latter, said cam element being constructed and arranged to flex the needle whereby to 40 bring its beard into closing contact with the presser.
9. A machine of the class described having in combination a support provided with a needle guideway, a needle movable in said 45 guideway, means for moving the needle longitudinally of said guideway, and a device movable along said guideway and having an element engageable with a portion of the needle shank whereby to flex the hook end 50 of the needle outwardly of said guideway during its longitudinal movement therein.
10. In a knitting machine in combination, a needle support having a needle slot therein, a needle movable longitudinally of said slot, 55 a device movable in said slot and positioned to the rear of the needle and a cam element carried by said device and constructed and arranged to contact with a portion of the needle shank whereby to flex the hook end 60 of the latter outwardly of the slot.
11. In a knitting machine in combination, a needle provided with an outstanding hump in its shank portion and means coöperating with said hump for transversely flexing the hook end of the needle outwardly of its 65 groove.
12. In a knitting machine in combination, a needle provided in its shank portion with a cam element; and a member having a complementary cam element constructed and ar- 70 ranged for contact with said first cam element, whereby to flex the hook end of the needle relatively to the butt portion thereof.
13. In a knitting machine in combination, a needle having a hook portion and a shank 75 portion, a cam incline carried by said shank portion, and means coöperative with said cam incline for imparting movement to said hook portion.
14. A knitting machine having in combi- 80 nation a longitudinally movable spring beard needle, a beard presser, a jack movable relatively to the needle, said jack having an element which by contact with the needle acts to flex the latter to bring its 85 beard into closing contact with the presser, cam means for actuating said needle and jack, said cam means presenting substantially parallel portions during the final portion of the stitch drawing movement of the 90 needle, and non-parallel portions during the first part of the succeeding elevation of the needle.
15. In a knitting machine in combination a spring beard needle and means for actu- 95 ating the same, a presser for the needle beard, and means including a cam having a dwell portion for imparting a relative beard pressing movement to said devices, said means being constructed and arranged to 100 accelerate the time of release of the needle beard as respects its period of closure.
16. In a knitting machine in combination a spring beard needle, cam means including a cam having a dwell portion for actuating 105 the same and means for closing the needle beard, said means being constructed and ar- ranged to close the beard and maintain it closed throughout a substantial portion of the stitch drawing movement of the needle 110 and to permit the beard to fully open at a relatively early time in the upward move- ment of the needle.
17. In an independent needle knitting ma- 115 chine, in combination a needle cylinder, a series of spring-beard needles slidable thereon and provided with humps on their shanks, a beard presser member, a cam cylinder, needle cams therein, a series of jacks asso- 120 ciated with the respective needles, and cams in said cam cylinder for actuating said jacks whereby said jacks are brought into opera- tive engagement with said humps to flex the needles transversely.
- Signed by me at Philadelphia, Pennsyl- 125 vania, this 12th day of May, 1920.

WILLIAM SCHWARZE.
